UNITED STATES PATENT OFFICE.

ALFRED J. DOUGHTY, OF ST. LOUIS, MISSOURI, ASSIGNOR, BY MESNE ASSIGNMENTS, TO CHICAGO PNEUMATIC TOOL COMPANY, A CORPORATION OF NEW JERSEY.

BLANK FOR HAMMER-HANDLES.

SPECIFICATION forming part of Letters Patent No. 730,887, dated June 16, 1903.

Application filed August 4, 1899. Serial No. 726,104. (No model.)

To all whom it may concern:

Be it known that I, ALFRED J. DOUGHTY, a citizen of the United States of America, residing at the city of St. Louis, in the State of Missouri, have invented a certain new and useful Blank for Hammer-Handles, of which the following is a description, reference being had to the accompanying drawings, forming part of this specification.

10 My invention relates more particularly to a novel blank for pneumatic-hammer handles composed of a grasping portion or handle proper, an attaching portion for connecting the handle to the cylindrical body of the tool, and an intermediate curved connecting portion or neck, and in which an air-inlet passage or duct extends entirely through the handle and neck portions for the admission of a motive fluid to the tool from a supply-pipe connected to the handle. Such handles are shown, for instance, in Letters Patent of the United States No. 549,102 and No. 575,589, granted to Joseph Boyer November 5, 1895, and January 19, 1897, respectively. The 15 Boyer pneumatic hammers shown and described in these patents, including the handles referred to, have gone into extensive use; but great difficulty has been experienced in making the handles of them. Heretofore 20 until recently said handles have been made of malleable-iron castings and have had the air-inlet passage formed in them by coring. Owing to the peculiar shape of the handle and to the fact that a comparatively large passage with comparatively thin walls (particularly in the neck portion of the handle) is required, great care has been necessary in the manufacture of the handles, and even when such care has been exercised a great many defective castings are produced. Inasmuch as the air-inlet passage through the handle is required to convey motive fluid to the tool under a high pressure, frequently exceeding one hundred pounds to the square inch, it follows that a perfect casting is required for the production of a satisfactory handle. Under the conditions above described the production of such handles has heretofore been very troublesome and expensive, owing to the

loss of a large proportion of defective castings; but notwithstanding such fact all manufacturers of tools having such handles have, I believe, heretofore made such handles of malleable-iron castings, except, perhaps, a few made of brass. The preferable method 55 of forming such blanks consists in drop-forging the "handle-blank" or solid handle from steel in approximately straight form, then drilling the air-inlet passage in said blank or solid handle while remaining in such approximately straight form, then heating the forging to the proper degree for bending, and then bending it into the desired handle shape and completing it ready for attachment to the tool, all as will be now described by reference to the accompanying drawings, wherein the preferable form of blank is shown, and in which—

Figure 1 represents the drop-forged steel blank or solid handle; Fig. 2, a middle longitudinal section thereof after the air-passage has been drilled in the same; Fig. 3, a view corresponding to Fig. 2 after the valve-chamber and supply-pipe connection have been formed in the grasping portion of the handle 75 and the attaching end of the handle finished ready for connection to the body of the tool, and Fig. 4 a middle vertical section of the completed handle.

The same letters of reference are used to 80 indicate identical parts in all the views.

In Fig. 1, A represents the grasping portion of the handle-blank, B the end which is formed into the attaching portion, and C the intermediate connection neck portion. Upon 85 the end of the portion A is formed a boss a, which is bored out and interiorly threaded in the completed handle to form a suitable connection for the nipple or coupling of the supply-pipe. The end B of the handle-blank 90 in the forging of Fig. 1 consists of a solid cylindrical block.

To complete a handle from the blank shown in Fig. 1, a straight air-passage D is drilled therein, as shown in Fig. 2, which is shown 95 as directed inward from the end B of the blank. The handle-blank may now be bent into handle form, Fig. 4, and the handle after-

ward completed, as shown in said figure, or the work indicated in Fig. 3 may be done upon the blank of the handle before it is bent into handle shape. Such work consists in boring 5 out the valve-chamber E from the end of the handle opposite that into which the air-passage D was drilled, such valve-chamber intersecting the air-passage D, as shown, and completing a passage-way entirely through 10 the handle, boring out the supply-pipe connection F and interiorly threading it, and completing the attaching end B of the handle, as shown, consisting, chiefly, in boring out and interiorly threading it and cutting a 15 circular groove in the base of its interior chamber, which groove is intersected by the air-passage D. The outer end of the passage D is permanently closed by a plug c, driven into a suitable recess formed to receive it. 20 The straight blank of Figs. 2 and 3 is heated to the proper degree for bending and bent into the shape shown in Fig. 4, after which 25 passages b are drilled in the portion B. The handle may then be equipped with a throttle- valve of any suitable type, which will complete the handle ready for attachment to the tool.

While my invention relates more particularly to drop-forged blanks, some of the advantages of my invention may be obtained 30 by casting the blank or solid handle of Fig. 1 of steel, which in producing the completed handle could be subsequently treated by drilling the passage-way D in it, as shown in Fig. 35 2, or completing it as far as shown in Fig. 3 and then heating it to the proper degree for bending and bending it into handle shape, as in Fig. 4; but the handles which I have made and put into successful and extensive use, as 40 heretofore stated, have been produced by

drop-forging and are superior to those which may be produced from steel castings.

Having thus fully described my invention, I claim—

1. The herein-described blank for hammer-handles, comprising a grasping portion, an attaching portion, and a neck portion substantially in line, said blank having a substantially straight air-passage extending from the attaching portion through the neck to the 50 grasping portion, and said blank being adapted to be bent into handle form.

2. The herein-described blank for hammer-handles, comprising a grasping portion, an attaching portion and a reduced neck portion 55 substantially in line, said blank having a substantially straight air-passage, extending from the attaching portion through the neck to the grasping portion, said grasping portion having a valve-chamber therein, and said blank being adapted to be bent into handle form, substantially as described.

3. The herein-described blank for hammer-handles, comprising a grasping portion, an attaching portion and a reduced neck portion, 65 all substantially in line, said blank having a substantially straight air-passage, extending from the attaching portion through the neck portion into the grasping portion, said grasping portion having a valve-chamber therein, 70 at an angle to and connecting with said air-passage, said attaching portion having a chamber therein communicating with said air-passage, and said blank being adapted to be bent into handle form, substantially as described. 75

ALFRED J. DOUGHTY.
